Patented Dec. 15, 1959

186,863

COMBINATION GOOSE AND DUCK CALLER

Frank J. Testo, Elkhart, Ind.

Application January 2, 1959, Serial No. 54,026

Term of patent 14 years

(Cl. D72—1)

FIG. 2

FIG. 1

FIG. 3

FIG. 5

FIG. 4

FIG. 6

Figure 1 is a side elevational view of a combination goose and duck caller, showing my new design;

Figure 2 is a top plan view;

Figure 3 is a bottom view;

Figure 4 is a side elevational view, showing the side opposite the one shown in Figure 1;

Figure 5 is an end elevational view taken from the right of Figure 1; and

Figure 6 is an end elevational view taken from the left of Figure 1.

The essential features of my design reside in the portion shown in full lines.

I claim:

The ornamental design for a combination goose and duck caller, substantially as shown and described.
